ATTORNEY

UNITED STATES PATENT OFFICE.

ALPHA O. TAYLOR, OF BLUECREEK, WEST VIRGINIA.

CALIPERS.

1,269,336.

Specification of Letters Patent. Patented June 11, 1918.

Application filed December 8, 1915. Serial No. 65,755.

To all whom it may concern:

Be it known that I, ALPHA O. TAYLOR, a citizen of the United States, residing at Bluecreek, in the county of Kanawha and State of West Virginia, have invented certain new and useful Improvements in Calipers, of which the following is a specification.

An object of my present invention is to provide a new and improved device which embodies the necessary requisites for ascertaining both the interior and exterior diameters of pipes and other similar articles so as to obviate the necessity of the operator changing from one device to another when endeavoring to ascertain these measurements and to increase, to a material extent, the general utility of a device of this character.

A further object of my invention is to provide an improved device of the type in question that is extremely simple in construction, strong and durable, and highly practical from both the standpoint of the manufacturer and the standpoint of the user; and which, it is believed may be manufactured at a minimum cost.

Various other objects and advantages will become apparent during the continuance of the following description, therefore further detailed description is deemed unnecessary.

These objects are accomplished by such means as are shown in their preferred form in the accompanying drawings, described in the following specification and then more specifically pointed out in the appended claim.

In the accompanying drawings wherein like characters designate like parts throughout the several views;

Figure 1 is a view in front elevation of my improved device showing my device as in its preferred embodiment and in a position for ascertaining the exterior diameter of a pipe or the like article.

Fig. 2 is a sectional view taken on line 2-2 of Fig. 1.

Fig. 3 is a view in rear elevation showing my device in a position to ascertain the interior diameter of a pipe or the like article.

In the accompanying drawings, the numeral 10 designates the body portion or dial of the device, which is to be provided with suitable graduations, such as will be herein-after pointed out. A suitably curved arm 11 is fixed to the body 10 at a certain point about its perimetral edge and bent to project

therefrom in a plane corresponding with the plane of the general extent of the body portion. I employ a second arm 12 to act in conjunction with the arm 11 and provide the same with an enlargement 13 at one end to facilitate its connection with the body 10. The body 10 and the enlargement 13 of the arm 12 are provided with registering openings which receive a suitable fastening member 14 or point. In order to obviate the displacement of the fastening member and at the same time provide for the efficient operation of the arm 12, I provide a plate 15 which receives one end of the fastening member as clearly shown in Fig. 2. In order to indicate the position of the arm 12 upon the body 10, by co-action with the graduations thereon, I provide the enlargement 13 of the arm 12 with a suitable indicating finger 16. When the arms are in the position shown in Fig. 1, it is contemplated to have the finger 16 register with the zero mark of the graduations so that when the arms 11 and 12 are moved in order to engage with the exterior periphery of the article to be measured, the distance between the free ends of the arms will be indicated by the finger 16.

In order to render the device applicable for use in ascertaining inside diameter of a pipe such as illustrated by the letter A in Fig. 3, the arm 12 may be moved entirely around the body 10 into the position shown in Fig. 3, or it may be moved into such position by springing the spherical ends of the respective arms 11 and 12 past one another and continuing to move the arms to the position shown. When in this position movement of the free ends of the arms will also be recorded by the indicator finger 16 in view of the fact that the graduations to one side of the body 10 are for use in ascertaining the inside diameter while the graduations to the other side are only used when it is desired to ascertain the outside diameter of an article.

The zero graduation is located on the dial at a point exactly in alinement with the pivotal center of the arcuate dial face and the contact face of the hemispherical end of the arm 11, and the point of the indicating finger 16 is located between and exactly in alinement with its pivotal center and the contact face of the hemispherical end of the arm 12; so that when these hemispherical ends are in contact with one another, the in-

dicator finger 16 exactly registers with the zero graduation of the dial.

From the foregoing it will be appreciated that I have provided an extremely simple device which embodies the necessary requisites for ascertaining the inside and outside diameters of an article. It is also believed that the other advantages and novel features of my invention will be readily understood and therefore further detailed description is deemed unnecessary.

In reducing my invention to practice I find that the form referred to herein as the most practical and preferred embodiment is the most efficient, but realizing that certain conditions will necessarily vary in concurrence with the adoption of my device, I desire to emphasize the fact that various minor changes in the details of construction and in the proportion of parts may be resorted to when required without sacrificing any of the advantages of my invention as defined in the appended claim.

Having thus fully described my invention,

what I claim as new and desire to secure by 25 Letters Patent is:

Calipers comprising a pair of measuring arms one of which is provided with a dial having graduations thereon beginning at zero and progressing in two arcuate and opposite series from said zero which latter is between and in alignment with the center of graduation of said dial and the contact point of its measuring arm, the other arm of said pair being ungraduated and being mounted 25 to turn about said center and being provided with an indicating finger extending toward its point of contact with said other arm, so as to register with said zero when the contact points of said arms are touching one 40 another.

In testimony whereof I affix my signature in presence of two witnesses.

ALPHA O. TAYLOR.

Witnesses:

CHLOE COPENHAVER,

L. C. JARRETT.
